UNITED STATES PATENT OFFICE.

ALBERT KAMINSKI, OF PITTSBURGH, PENNSYLVANIA, ASSIGNOR OF ONE-HALF TO
ANDREW A. GMYS, OF PITTSBURGH, PENNSYLVANIA.

PARACHUTE.

1,344,044.

Specification of Letters Patent. Patented June 22, 1920.

Application filed December 17, 1919. Serial No. 345,459.

To all whom it may concern:

Be it known that I, ALBERT KAMINSKI, a citizen of Poland, residing at Pittsburgh, in the county of Allegheny and State of Pennsylvania, have invented certain new and useful Improvements in Parachutes, of which the following is a specification.

This invention relates to certain new and useful improvements in parachutes and has more particular reference to that type of 10 parachute embodying a screw propeller provided with foldable blades so as to be normally retained in inoperative condition, means being provided to release the blades 15 and to rotate the propeller at will.

The invention resides in certain combinations and arrangements of parts as will be hereinafter fully described and pointed out in the appended claims.

In the drawings, wherein like reference characters indicate corresponding parts throughout the several views,

Fig. 1 is an elevational view, partly broken away and partly in vertical section, of a parachute constructed in accordance with the present invention and with the wings or blades of the propeller inoperatively positioned.

Fig. 2 is a view similar to Fig. 1 with the propeller blades operatively disposed.

Fig. 3 is a view partly in section and partly in top plan and taken upon line III-III of Fig. 2.

Fig. 4 is a side elevational view, with parts removed and parts broken away, of the device shown in Fig. 1.

Fig. 5 is a fragmentary detail view on an enlarged scale, showing the mounting of the propeller blades.

Fig. 6 is a fragmentary detail view illustrating the gearing provided between the motor shaft and the shaft of the propeller.

Fig. 7 is a view of the device shown in Fig. 6, partly in top plan, and partly broken away, and

Fig. 8 is a fragmentary sectional detail view of the telescopic members which connect the propeller with the blade retaining member.

Referring more in detail to the several views, the present invention embodies a stiff plate 4 adapted to be firmly fastened against

and to a person's back by means of suitable straps 6 or the like, the said plate 4 being coupled with the propeller blade retaining member 7 by a suitable flexible member 8.

The retaining member 7 is in the form of a pan and has the lower end of tube 9 rigidly fastened centrally to its bottom as at 10, said tube 9 extending upwardly from and perpendicularly to said bottom. Another tube 11 is slidably disposed in the tube 9 and is prevented from moving out of the latter by the provision of suitable shoulders 12. (See Fig. 8.) A third tube 13 is slidable within the tube 11 and limited in outward movement by shoulders 14, said tube 13 constituting the shaft of the propeller 15 and being journaled in bearings 16 provided in the bars 17 which connect rigidly the casings 18 of the motors 19.

The propeller 15 embodies a hub in the form of a disk 19 which is rigidly secured upon the tube 13. The disk 19 has a plurality of singularly disposed and radially arranged blades 20 pivoted thereto as at 21 for vertical swinging movement, the inner ends of said blades being arranged to engage the periphery of the disk 19 when said blades are substantially horizontally disposed so as to prevent the blades from swinging upwardly too far. As seen in Fig. 1 the blades 20 may be swung downwardly to an inoperative position and there retained by the rim of the member 7. This is accomplished by moving member 7 and tube 9 downwardly below the outer ends of the blades, and, after the blades are all swung downwardly, the member 7 and tube 9 are moved upwardly so as to bring the rim of the member 7 in the position wherein the same surrounds the outer ends of the blades 20.

Another smaller disk 22 is secured upon tube 13 and the inner ends of springs 23 are rigidly fastened as at 24 to said disk 22, a spring 23 being provided above each blade 20 as shown in Fig. 3, and each spring having its outer end connected by a yieldable and flexible member 25 to a blade 20. The springs 23, normally tending to move upwardly, function to move the blades to their operative position. It will thus be seen, that when an upward pull is exerted upon the

tube shaft 13 and a downward pull is exerted upon member 7, the latter member will be moved to disengage its rim from the free ends of the blades 20, whereupon the springs 23 immediately raise the blades 20 to their operative position.

A bevel gear 26 is rigidly fastened upon the shaft 13 between the bearings 13 and the bevel pinions 27 provided on the motor shafts 28 of the motors 18 mesh with this bevel gear. The blades 20 of the motors 18 are fastened upon the shafts 28 so that when said blades are impinged by a motive agent, the propeller 15 will be rotated for starting the fall of the person using the parachute.

A suitable container, such for example, as a balloon 30, is provided for holding a motive agent under pressure for actuating the motors 18, said balloon being interiorly connected by suitable conduits 31 with the interior of the motors 18. The conduits 31 have suitable controlling valves 32 disposed therein so as to provide for the starting or stopping of the motors 18 as desired, a suitable member 33 being extended to a point within reach of the user of the parachute for opening said valves. As shown, the valves 32 are adapted to normally close and may be opened by a downward pull upon the member 33 which is preferably in the form of a rope and which preferably extends down through the tubes 9, 11, and 13.

The operation of the present device may be briefly described as follows:

When the plate 5 has been securely strapped against the back of the user of the parachute and the parts are disposed in their normal positions as shown in Fig. 1 the user jumps from, for instance, an aeroplane and thereby immediately causes a downward pull to be exerted upon the blade retaining member 7 so that the blades are released and raised to the position shown in Fig. 2. The operator then pulls upon the cord or rope 33 so as to open the valves 32 as seen in Fig. 3. The motive agent, such as air under pressure immediately passes from the container 30 through the conduits 31 and impinges the blades 20 of the motors 18, thereby causing rotation of shafts 28, pinions 27, gear 26 and shaft 13. Rotation of shaft 13 is communicated to the propeller 15 for exerting a lifting force so as to stay the fall of the operator and permit him to land in safety. Obviously, the speed at which the propeller is rotated and the lifting force consequently obtained may be varied according to how widely valves 32 are opened.

It will thus be seen that I have provided an efficient parachute which is reliable in operation as well as practical and durable in construction.

It is to be understood that various changes may be made in the forms, combinations and

arrangements of parts without departing from the spirit and scope of the invention as claimed.

What is claimed as new is:

1. A parachute including a propeller having wings foldable downwardly to an inoperative position, means slidably connected to the propeller adapted when in one position to engage the free ends of the propeller blades and retain the same inoperatively disposed and movable to a position to release the blades, means to automatically raise the blades to a substantially horizontal operative position when released, and means to rotate said propeller.

2. A parachute including a propeller having wings foldable downwardly to an inoperative position, means slidably connected to the propeller adapted when in one position to engage the free ends of the propeller blades and retain the same inoperatively disposed and movable to a position to release the blades, means to automatically raise the blades to a substantially horizontal operative position when released, means to rotate said propeller, and means attached to the blade retaining means for fastening the parachute to a person's body.

3. A parachute including a propeller having wings foldable downwardly to an inoperative position, means slidably connected to the propeller adapted when in one position to engage the free ends of the propeller blades and retain the same inoperatively disposed and movable to a position to release the blades, means to automatically raise the blades to a substantially horizontal operative position when released, means to rotate said propeller, said last named means including a motor connected with and disposed above said propeller and a motive agent container above said motor.

4. A parachute including a propeller having wings foldable downwardly to an inoperative position, means slidably connected to the propeller adapted when in one position to engage the free ends of the propeller blades and retain the same inoperatively disposed and movable to a position to release the blades, means to automatically raise the blades to a substantially horizontal operative position when released, means to rotate said propeller, a valve to control the flow of the motive agent from the container to the motor, and means to operate said valve extended downwardly to a point adjacent the blade retaining means.

5. A parachute including a pan-shaped blade retaining member having means attached thereto for fastening the same to the body of a person, a tube rigidly fastened to and extending perpendicularly upwardly from the bottom of said pan-shaped blade retaining member, another tube slidably disposed within the first named tube and limit-

- ed against outward displacement from the latter, a shaft slidable in the second named tube and having a plurality of blades pivoted thereto for swinging downwardly to 5 an inoperative position, the rim of said pan-shaped member arranged to surround the free ends of said blades when upwardly positioned for retaining the blades in their inoperative positions, means to normally 10 move the blades to a substantially horizontal operative position when released from said pan-shaped member, and means to rotate said shaft.
6. A parachute including a pan-shaped 15 blade retaining member having means attached thereto for fastening the same to the body of a person, a tube rigidly fastened to and extending perpendicularly upwardly from the bottom of said pan-shaped blade 20 retaining member, another tube slidably disposed within the first named tube and limited against outward displacement from the latter, a shaft slidable in the second named tube and having a plurality of blades pivoted thereto for swinging downwardly 25 to an inoperative position, the rim of said pan-shaped member arranged to surround the free ends of said blades when upwardly positioned for retaining the blades in their inoperative positions, means to normally 30 move the blades to a substantially horizontal operative position when released from said pan-shaped member, means to rotate said shaft, said last named means comprising a pair of rigidly connected 35 motors arranged at opposite sides of said shaft, and means to operate said motors.

In testimony whereof I affix my signature.

ALBERT KAMINSKI.
